UNITED STATES PATENT OFFICE

CHARLES V. COLVIN AND RICHARD A. FOSTER, OF LANSING, MICHIGAN

KITCHEN VENTILATOR

Application filed September 12, 1930. Serial No. 481,535.

This invention relates to ventilators, more particularly to apparatus including a fan and motor whereby the fan is driven, which are arranged upon or in some manner associated with a hood or canopy in kitchens. Air and fumes are drawn by the fan into the hood and exhausted therefrom by way of a suitable uptake or outlet leading to the exterior of the building.

10 The object of this invention is the production of such construction having parts of special formation and disposition and intended to be applied to a hood which constitutes the base or bottom of a compartment which is plastered on the outside in the same manner as the ceiling and walls of the room, and the arrangement with respect to the hood being so made as to permit the motor and fan to be removed downwardly through 15 the hood for inspection or repairs without disturbing the hood or breaking any plaster.

In the accompanying drawing is illustrated one combination of the parts comprising this invention, and Fig. 1 shows all the parts 20 assembled with this invention applied to a hood. Fig. 2 represents the top of the hood with all other parts removed, and illustrates the opening in the top. Fig. 3 is a top view of the fan casing only.

25 Throughout the drawing and description the same number is used to refer to the same part.

Considering the drawing, the ceiling 1 of the room has extending downwardly a frame 30 2 by which is formed a chamber designated as a whole by the numeral 3. The chamber is plastered and white coated on the outside and around an opening in its bottom to preserve the appearance of the room. In the 35 opening in the bottom of chamber 3 is secured the rim of the hood 5, which may be arranged against the plaster 4 as shown, or on top of the boundary of the opening of the chamber. As illustrated, the hood may be 40 detached, and removed as a whole without disturbing the plastering.

In the top of the hood as best shown in Fig. 2 is an opening 6, and within the hood below the opening 6 is attached a plate 7.

50 The plate may be detached from the hood,

and the plate has an opening or openings 8. Upon the plate 7 is located a fan casing 9 which is made with an opening or openings 10 in its bottom arranged to register with the openings of the plate 7. Within the fan 55 casing upon the bottom thereof is a rotatable damper plate 12 operated by means of the handle 13. The damper plate is not essential, but is advantageous under certain circumstances set out in the statement of the 60 operation.

The fan 14 is driven by a motor 15 the armature of which may be carried by a step ball bearing 16 resting upon a plate 17 which constitutes the top of the fan housing. The 65 motor may be protected by a cover 18 removably secured to the plate 17. This invention is in no way limited as to the character or size or structure of the motor and fan elements. The motor may be connected by 70 conductors 19 and 20 with a wall switch 21 of customary pattern.

As set out in Figs. 1 and 3 the fan casing has the usual tangential outlet 22, and this is introduced for a short distance into the elbow 75 23 of an outlet conduit which may pass upwardly through the ceiling 1 and to the outside of the building.

It is believed to be within the purview of this invention to employ the hood in any 80 position with or without the plastered chamber 3, and the particular shape of the hood is not important.

In explaining the operation of this invention, attention is called to the fact that as 85 illustrated in Fig. 1 the fan casing 7 is located at one end of the opening 6 of the hood when the outlet 22 is introduced into the elbow 23. Now, if the plate 7 is detached, the fan casing may be moved to the left hand and 90 the outlet 22 will be withdrawn from the elbow 23. This procedure permits the fan casing and motor to be tilted and with a little care the motor and fan may be passed downwardly through the opening 6 of the hood. 95 The fan and motor are replaced by contrary movements, and when the casing 9 is moved to the right hand the outlet 22 again passes into the elbow 23.

Air and fumes are drawn into the hood and 100

discharged by the fan, and the volume of the air entering the fan may be controlled by the damper plate 12. If the entrance openings into the fan are wide open and the fan is operated at sufficient speed, the air may be drawn from the entire lower floor or upper floors, and in this way the air may be changed throughout a dwelling by means of the single ventilating devices herein shown and described.

10 Having now described this invention, and explained the manner of its use, we claim:—

1. In a ventilator, the combination with a hood having an opening in the wall thereof,

15 of a fan and motor therefor, a fan casing having an outlet pipe, an air conduit, the said outlet pipe constructed to be removably inserted in said air conduit, the said motor and fan being supported upon the hood in detachable relation thereto, said motor and

20 fan casing being removable together through said opening in the hood thereby withdrawing said outlet pipe from said conduit.

2. In a ventilator, the combination with a hood having an opening in the wall thereof,

25 of a fan and motor therefor, a fan casing having a tangential outlet pipe projecting horizontally at one side, an air conduit, the said outlet pipe and conduit being respectively constructed and arranged whereby the

30 outlet pipe may be removably inserted into said conduit, the said motor and fan casing being supported upon the hood in detachable relation thereto, said motor and fan casing being removable through the said opening in the hood thereby withdrawing said outlet from said conduit.

In testimony whereof we affix our signatures.
